UNITED STATES PATENT OFFICE.

JOHN WESLEY FREEMAN, OF DENVER, COLORADO.

WRENCH.

SPECIFICATION forming part of Letters Patent No. 670,132, dated March 19, 1901.

Application filed January 5, 1901. Serial No. 42,233. (No model.)

To all whom it may concern:

Be it known that I, JOHN WESLEY FREEMAN, a citizen of the United States, residing at Denver, in the county of Arapahoe and State of Colorado, have invented a new and useful Wrench, of which the following is a specification.

This invention relates to wrenches, and has for its object to provide for the quick and convenient release of the movable jaw of a wrench by the hand which grasps the handle thereof and also to arrange for the locking of the said movable jaw by the same hand without removing the latter from the handle of the wrench, so that the movable jaw may be conveniently locked and released by one hand, while the jaw may be adjusted by the other hand.

With this and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is an elevation of a wrench embodying the present invention. Fig. 2 is a central longitudinal sectional view thereof. Fig. 3 is a transverse sectional view taken on the line 3 3 of Fig. 2. Figs. 4, 5, and 6 are similar to the preceding views and illustrate a slightly-modified assemblage of parts.

Like characters of reference designate corresponding parts in all of the figures of the drawings.

Referring to the drawings, 1 designates the shank of the wrench, which is provided with the fixed jaw 2 at one end and the handle 3 at the opposite end thereof. The inner edge 45 of the shank is provided with a longitudinal groove 4, which extends for the entire length of the shank and also extends throughout the inner side of the handle.

The slidable jaw 5 embraces the shank and 50 has a stem 6, which is slidably received within the groove of the shank and is toothed upon its outer side, so as to provide a rack 7,

exposed through the open outer side of the groove.

At the inner end of the handle there is a 55 fixed cuff 8, which embraces the shank and is provided in its upper inner side with a slot or notch 9 and the opposite perforate ears 10, projecting at opposite sides of the notch.

The means for locking the slidable jaw at 60 any adjustment upon the shank of the wrench comprises a locking-cam 11, which is mounted between the perforate ears 10 by means of a suitable transverse pivot-pin 12. The inner face of this cam is toothed to take into 65 the rack 7 or toothed face of the stem of the adjustable jaw and is also provided with a hand-operated lever 13, which closes flush into the groove in the handle, as shown in Fig. 2 of the drawings. When the lever is 70 pressed into the groove of the handle, the locking-cam is locked against the stem of the slidable jaw, and to release the jaw the lever is thrown slightly outward, so as to clear the toothed portion of the cam from the stem of 75 the jaw, whereby the latter may be freely adjusted to any position upon the shank and then relocked by pressing inwardly upon the cam-lever.

To facilitate the opening or releasing of the 80 cam-lever, a finger-piece 14 is provided upon the inner end of the lever and arranged radially with respect to the pivotal support of the locking-cam, so that the thumb of the hand which grasps the handle may lie in convenient reach of the finger-piece, as indicated by dotted lines in Fig. 1 of the drawings, whereby a slight pressure or straightening of the thumb will throw the free end of the lever outwardly to release the locking-cam. It will 85 of course be understood that the pressure of the hand upon the lever is relieved sufficiently to permit of the slight movement required for the release of the cam, and by again pressing upon the lever the jaw may be locked. Thus 90 one hand is employed to lock and release the slidable jaw, while the other hand is free to adjust the jaw. By this arrangement the locking and releasing of the jaw are greatly 95 facilitated and the constant pressure of the hand upon the locking-lever precludes the possibility of the jaw becoming accidentally released.

In the form of the wrench shown in Figs.

4, 5, and 6 the shank of the wrench is not grooved, and the stem 6^a merely slides against the adjacent face of the shank. Also the shank is provided at its handle end with a 5 screw-threaded spindle portion 15, which passes loosely through a corresponding bore in the handle 3 and projects at the outer end thereof for the reception of a nut 16, so that the handle and the movable jaw may be conveniently removed. The handle also has the 10 groove for the reception of the lever, and a suitable filling-strip 17 is interposed between the screw-threaded spindle and the lever, so as to form the back of the groove. In all 15 other respects the two forms of the wrench are the same.

What is claimed is—

1. A wrench, comprising a shank, a fixed 20 jaw, a handle, an adjustable jaw slidably mounted upon the shank, an operating-lever fulcrumed upon the shank and having an interlocked engagement therewith, and also provided with a releasing thumb-piece arranged adjacent to the inner end of the lever 25 and in position for engagement by the thumb of the hand which grasps the handle of the wrench.

2. A wrench, comprising a shank, a fixed 30 jaw at one end thereof, a handle at the opposite end, an adjustable jaw slidably mounted

upon the shank, a cam-lever fulcrumed upon the shank and having an interlocked engagement with the slidable jaw, and a releasing thumb-piece carried by the inner end of the lever and disposed radially with respect to 35 the fulcrum of the lever.

3. A wrench, comprising a shank having a longitudinal groove in its inner side, a fixed jaw at one end of the shank, a handle at the opposite end thereof, and provided with a 40 groove forming an extension of the groove in the shank, an adjustable jaw slidably mounted upon the shank and having a toothed stem slidably received within the groove thereof, opposite bearing-ears projecting at opposite 45 sides of the groove, a toothed locking-cam pivoted between the ears and having a locking engagement with the toothed portion of the stem, a hand-operated lever projecting from the cam and normally lying within the 50 groove within the handle, and a releasing thumb-piece projecting radially from the cam.

In testimony that I claim the foregoing as my own I have hereto affixed my signature in the presence of two witnesses.

JOHN WESLEY FREEMAN.
